UNITED STATES PATENT OFFICE

149,099

DESIGN FOR A PUSH PIN

Hobert E. Sweet, Providence, R. I., assignor to
H. E. Sweet Manufacturing Co., Providence,
R. I., a partnership composed of Hobert E.
Sweet and Hobert E. Sweet, Jr.

Application July 25, 1946, Serial No. 131,926

Term of patent 14 years

(Cl. D54—9)

To all whom it may concern:

Be it known that I, Hobert E. Sweet, a citizen of the United States, residing in Providence, county of Providence, and State of Rhode Island, have invented a new, original, and ornamental Design for Push Pin, of which the following is a specification, reference being had to the accompanying drawing, forming a part thereof.

Fig. 1 is a plan view of a push pin showing my new design;

Fig. 2 is a side view; and

Fig. 3 is a perspective view thereof.

I claim:

The ornamental design for a push pin, substantially as shown.

HOBERT E. SWEET.
